VALVE GUIDE

Paul J. Marten, San Francisco, Calif.

Application August 10, 1937, Serial No. 158,359

1 Claim. (Cl. 4—57)

This invention relates to improvements in guides for flush tank valves.

The primary object of my invention is to provide a new and improved flush valve guide means adapted for use with standard flush valve equipment to insure a correct seating of the valve and the complete closure thereof to prevent the flow of water therethrough.

An object of my invention is to provide an improved flush valve guide means adapted to be detachably affixed to flush valve mechanisms of various kinds.

Another object of my invention is to provide an improved flush valve guide means which is capable of being adjusted to permit its use with valves of various sizes.

Other and further objects of my invention will be pointed out hereinafter, indicated in the appended claim or will be obvious to one skilled in the art upon an understanding of the present disclosure. For the purposes of this application I have elected to show herein certain forms and details of a guide for flush valves representative of my invention; it is understood, however, that the embodiment of my invention herein shown and described is for the purpose of illustration only, and that therefore it is not to be regarded as exhaustive of the variations of the invention, nor is it to be given an interpretation such as might have the effect of limiting the claim short of the true and most comprehensive scope of the invention in the art.

In the accompanying drawing:

Fig. 1 is a perspective view showing a standard flush valve and the adjustable guide means constituting the subject of the present invention operatively associated therewith; and

Fig. 2 is a perspective view of my improved valve guide means.

Referring to the drawing the numeral 1 designates the fitting of a standard flush valve having a depending threaded outlet portion 2 for securing the valve in the bottom of a water closet tank (not illustrated). The upper end of the fitting 1 is provided with a suitable seat 3 for a valve 4. Secured to one side of the fitting 1 is a tubular overflow connection 5 having an upright overflow pipe 5' supported thereon. The valve 4 is buoyant and its lower portion is semi-spherical in shape so it will suitably engage the seat 3 to prevent the passage of water therethrough.

The usual means for operating the valve 4 comprises a vertically disposed lift rod 6 secured at its lower end to the said valve and supported

in an upright position by means of a guide sleeve 7 formed on an arm 8 which is secured to the overflow pipe 5'. The upper end of the lift rod is arranged for the attachment of an operating lever (not shown).

The valve 4 is normally held upon the seat 3 by the pressure of the water in the tank, but when it is raised upwardly through the lifting of the rod 6 the water in the tank will flow through the fitting 1 to the water closet, and when the operating lever is again released, the weight of the valve will cause it to drop downwardly upon the seat to again effect the closing of the latter.

It frequently happens that the valve 4 while descending to its normal position on the seat 3 is carried by the water entering the tank or by the water passing through the fitting 1 to a position where it does not properly engage with the said seat, thereby failing to prevent the continued flow of water from the tank into the water closet. The failure of the valve 4 to become properly seated on the seat 3 results in a continued leakage of water through the valve, all of which is both annoying and wasteful.

In order that the aforesaid undesirable features might be eliminated, I have provided an improved guide means for insuring the proper seating of the valve 4 on its seat 3.

My improved guide means comprises a wire frame formed preferably from a single strand of wire which is bent so as to provide a semi-circular upper member 9, opposed but spaced vertical members 10, and a semi-circular lower member 11. The ends of the strand of wire constituting the frame are secured together, as at 12, by solder or a weld. The lower member 11 of the frame is bent upwardly as at 13 to accommodate the overflow connection 5. The size of the frame may be adjusted with respect to its diameter by bending the upper and lower semi-circular members 9 and 11 so the upright members 10 are positioned closer or farther from one another, depending whether the device is to be used with smaller or larger valves 4. Secured at their ends to the upper and lower upright members 9 and 11 are a plurality of substantially vertical bars 14 which constitute guide means for confining the reciprocating movement of the valve 4 within a fixed vertical path. Secured to two of the vertically disposed bars 14 which are located preferably at points opposite the opening in the frame between the two upright members 10, are a plurality of spring clips 15 which are adapted to be applied to the overflow pipe 5' so

as to maintain the guide means in its proper position with respect to the normal vertical path in which the valve 4 travels when moved to open and closed positions.

- 5 It is to be understood that the vertical position of the substantially cylindrical cage or frame which constitutes my improved valve guide means may be changed by sliding the spring clips 15 either upwardly or downwardly on the overflow pipe 5', and the interior dimensions of said frame or cage may be just as easily changed to accommodate valves of different sizes by bending the upper and lower semi-circular members 10 15 9 and 11 so their respective diameters are suitably increased or decreased.

What I claim is:

In a flush valve, a tubular fitting through which water is adapted to flow, a valve seat on the fitting, a valve adapted to engage the seat, an upright overflow pipe connected to the fitting, a substantially cylindrical guide member supported by the overflow pipe by a clip means and extending around the valve for guiding the valve into proper seating engagement with the seat, the said guide member comprising a flexible 10 wire bent so as to provide spaced semi-circular upper and lower members joined to one another by spaced but adjacent upright members, and a series of upright bars connected to the upper and lower semi-circular members.

PAUL J. MARTEN.
